UNITED STATES PATENT OFFICE

MAGGIE PITTMAN, OF KOSCIUSKO, MISSISSIPPI

DESIGN FOR A BLOUSE

Application filed April 29, 1932. Serial No. 43,656. Term of patent 7 years.

To all whom it may concern:

Be it known that I, MAGGIE PITTMAN, a citizen of the United States, residing at Kosciusko, in the county of Attala and State of Mississippi, have invented a new, original, and ornamental Design for Blouse, of which the following is a specification, reference being had to the accompanying drawing, forming a part thereof.

The stitch known as faggotting as shown in part in accompanying drawing is used to connect the strips of material in the same or similar manner through the entire blouse.

I claim:

The ornamental design for a blouse substantially as shown and described.

MAGGIE PITTMAN.
